DEEPWATER DREDGE

George B. Massey, Chicago, Ill.

Application June 30, 1948, Serial No. 36,202

12 Claims. (Cl. 37—71)

1 This invention relates to deep water dredging and particularly to dredges of the dragline type.

Its main objects are to provide a novel and improved form of apparatus that will best meet all of the problems of deep underwater excavation of blasted rock as well as other materials; to provide an improved adaptation of the dragline bucket principle of deep water dredging; to provide an improved dragline dredge mechanism which may be carried by and operated from a floating hull but which in its normal excavating operation will have no effect tending seriously to disturb the disposition of the hull or to shift the position of the hull with respect to the terrain in which it is operative; and to provide in such dredge improved means controllable from the hull for directing the operation of the bucket as regards the submarine area to be excavated.

A specific embodiment of this invention is schematically illustrated in the accompanying drawings, in which:

Figure 1 is a top plan of a dragline dredge constructed according to this invention, including a partly diagrammatic representation of the operating mechanism.

Fig. 2 is a side elevation of the same; and

Fig. 3 is a detail in side elevation of a modified form of the dragline hauling mechanism.

In the form shown, the dredge comprises in general a floating hull 10 which has a well 11 extending vertically through it at approximately its center of buoyancy and proportioned to receive a heavy anchor block 12 designed to be suspended from said hull and to be lowered to rest freely upon the bottom of the body of water on which the hull floats so as to cooperate with mechanism for operating a dragline excavating bucket 13 without causing displacing strains on the hull.

With a view to simplifying this disclosure, the drawings are largely diagrammatic, with the omission of details of power plant, winches, motors and other mechanism well understood in the art and only incidentally related to the subject matter to be claimed herein.

The hull 10 is also provided with a second well 14 extending through its bottom from one end of the hull for a considerable distance inward from said end to provide clearance for hoisting mechanism for the bucket 13 in various positions. The length of this well is related to the length of cutting travel of the bucket.

A pair of trusses 15 extend along the sides of the well 14 and throughout the entire length of the hull and carry tracks 16 upon which ride the wheels of a traveling carriage 17 from which the bucket 13 is suspended by four cables 18 which pass over hoisting mechanism represented by the drums 19. After passing the drums 19, the cables 18 extend to counterweights 20, being guided

by appropriately located sheaves 12 and 22. The counterweights 20 are preferably hung outside of the hull from arms 23 carried by the carriage 17.

It will be understood that appropriate winch mechanism for severally manipulating the cables 18 to control tilting and hoisting movements of the bucket 13 is mounted on the carriage 17. Such mechanism is represented diagrammatically by the drums 19 and, as will be understood by persons familiar with this art, may be of such nature as to be controlled by an operator in an appropriate cab 24 on the carriage 17. The carriage 17 is mounted to travel on the rails 16 and may be propelled by winch mechanism represented diagrammatically by the drum 25 and cables 26 and 26.1.

A second carriage 27 is mounted on the rails 16 at the opposite end of the hull 10 and carries a counterweight 28 designed to counterbalance the weight of the carriage 17 including that of the bucket 13, its load and its counterweights 20. The carriage 27 is arranged to travel in counterbalancing relation to the travel of the carriage 17, to minimize disturbance of the hull during the hoisting and dumping operations of the bucket.

For example, in the design of the hull shown in the drawings where the normal center of buoyancy is nearer one end of the truss than the other, there is less room for travel of the carriage 27 than that of the carriage 17. Therefore, the weight of the carriage 27 and its counterweight may be assumed to be twice that of the carriage 17 and its load and the carriages would be driven so that the distance of the carriage 27 from the center of buoyancy would be at all times one-half of the distance of the carriage 17 from the center of buoyancy.

A diagrammatic representation of this relationship is shown in Fig. 1 where the cable 26 is attached to the forward end of the carriage 17, passes around the sheave 29, then over the driving drum 25 and then around a sheave 29.1 attached to the front end of the carriage 27 and then passes back to a fixed point 29.1 on the truss. A second cable 26.1 is attached to the rear end of the carriage 17, passes around a sheave 30 at the after end of the truss, then forward around a sheave 30.1 attached to the carriage and then back to a fixed point 30.2 on the hull. Thus movement of the carriage 17 in the operation of the bucket will always be associated with a counter-weighting movement of the carriage 27 in the opposite direction.

The anchor 12 is a rectangular block of heavy material, such as concrete, with bores 31 extending vertically through it to reduce the effect of suction when it is lifted from the ground and is provided with prongs 32 on its bottom surface so that it will grip the surface on which it rests.

The anchor block 12 is hung from four cables 33 in block-and-tackle arrangement for suspending, raising and lowering it and carries on its upper surface the dragline hauling mechanism for pulling a pair of cables 34 which are attached to opposite sides of the bucket 13. In practice the hoisting cables 33 may be attached to the four corners of the anchor block, while the sheaves from which these cables hang on the hull are preferably closer to the fore-and-aft center line of the hull to avoid capsizing of the hull in the event of breakage of one of such cables.

In the form indicated in Fig. 2, the dragline hauling mechanism comprises a pair of winch drums 35. The winch drums 35 may be exposed to the water, but their gearing and their electric motor are enclosed in a watertight housing 36 from which water may be excluded by air under pressure supplied by an armored tube 37 which passes over a sheave 38 and leads to appropriate power mechanism in a deck house 39 on the hull 10. The motor is similarly connected with its generator in the deck house 39 by a conductor cable 40 which may pass over a sheave, which together with the sheave 38 is mounted to travel vertically in a tower structure 41, as by a suspending cable 42 carrying a counterweight 43, which lifts these sheaves as the anchor 12 is lifted. The sheave 38 is, of course, large enough to prevent injury to the tube 37. Such lifting arrangement is indicated by dotted lines in Fig. 2, from which it will be understood that the movement of the sheave 38 need only be half that of the vertical movement of the anchor block 12.

In Fig. 3, instead of having the electrically driven winch mechanism enclosed in a housing mounted on the anchor block, the dragline hauling cables 34 of the bucket are led over sheaves 44 on the anchor block 12, then to sheaves 45 and then to winch mechanism in the deck house 39.

In this arrangement, the anchor block 12 would be of increased weight to compensate for the absence of the weight of the winch mechanism and for the upward pull on the cable 34 working against the weight of the block 12.

The horizontal disposition of the hull 10 with respect to the anchor block is controlled by two pairs of hawsers 46 and 47 leading respectively from points adjacent to the four corners of the anchor block 12 to four correspondingly related spaced points near the opposite ends of the hull where they enter hawseholes 48 and are connected to winches, not shown, whereby these hawsers may be manipulated to adjust the position of the hull with respect to the anchor.

The trusses 15 extend forward beyond the bow of the hull and the tracks for the carriage extend to a bumper block 49, where it will be in a position to empty the bucket into a barge 50 appropriately moored across the front of the hull as indicated in the drawing.

An illustrative example giving suitable dimensions for a dredge of this kind follows:

In horizontal contour the hull may be rectangular, 350 feet long, 85 foot beam, 19 feet deep at the after end and 13 feet deep at the forward end.

At the center of buoyancy of the hull is a well 40 feet by 60 feet. In this well is suspended a block of reinforced concrete 30 by 50 feet by 10 feet thick, weighing 750 tons. This block would be poured in place in layers or lifts. Prongs about 2 feet long would project downward in rows near the sides and ends of the block. The block is supported by four blocks and tackles mounted on the trusses which are 25 feet apart and run the full

length of the dredge and 50 feet beyond the bow. In view of the great weight of the anchor, the blocks and tackles are as close to the fore-and-aft center line of the hull at their upper ends as the lifting of the anchor will permit to avoid capsizing of the hull in the event of cable breakage.

Upon the anchor are two sets of 10-foot diameter grooved drag drums which, with a first set of gears, may be in the water. The rest of the gearing and the totally enclosed mill type, direct current motors are enclosed in two watertight rooms with an air pressure of 80 pounds per square inch to exclude water from these housing rooms. The air is cooled before being delivered to the housing by flexible tube or tubes 37 provided with a take-up arrangement. The compressor would preferably work on a closed circulation system with delivery and return tubes but might operate with a single tube with a pressure controlled discharge valve on the housing.

The electric current would be brought down in water-proof cables with take-up arrangement in the tower 41. Six large counterweighted sheaves carry the flexible air tubes and electric cables for two sets of winch mechanisms. One end of each such cable is attached to the hull and the other is attached on the anchor.

The drag drums are each grooved for a 2 $\frac{3}{4}$ inch diameter, 6 by 37 plow steel wire rope about 250 feet long with suitable flight rollers and sheaves to insure proper winding on the drums. The pull would be 150,000 pounds on each rope or 300,000 pounds stalling pull on the bucket.

The bucket is a 30 cubic yard dragline bucket with teeth on its cutting edge, two drag ropes and four hoist lines. The bottom of the bucket would be a grillage of beams leaving holes for passage of water. The rear end of the bucket would rise at 30° from the bottom and would be open.

The bucket weight and half of the live load of rock are counterweighted, resulting in a hoisting and lowering weight of 50,000 pounds. The bucket is 12 feet wide and the well in which it operates is 25 feet wide. The anchor block of concrete weighing 750 tons produces friction resisting horizontal motion of roughly 125 tons.

The speeds of operation are:

	Feet per minute
Anchor hoist	10
Bucket drag	100
Bucket hoist	200
Carriage travel	100

The motors operating the anchor hoist are preferably in synchronism. The same is true of the bucket hoist ropes, the drive of the two carriages and that of the two drag drums.

Power is supplied by two 1200 horsepower Diesel engines driving direct current generators with motors distributed as required.

	H. P.
Hoist anchor	500
Drag ropes	1000
Hoisting bucket	1000
Carriage drives	100
Air compressor etc.	300
Or a total while operating of	1500

The operation of the dredge will be apparent from the foregoing description. The bucket is filled by hauling on the draglines 34, then the bucket is tilted by manipulating the cables 18 to bring it to its load-carrying position shown by dotted lines 13.1. The carriage 17 is moved for-

ward or back with the bucket. As the bucket approaches the truss, the carriage is driven forward to the dumping position and the load is discharged by tilting the bucket.

To move the hull the anchor would be hoisted about 3 feet or more to provide clearance over obstructions on the bottom of the waterway.

The digging could be in a straight line or the bow of the hull could be swung about the anchor block, by manipulating the four mooring lines, represented in Figs. 2 and 3 by lines 46 and 47, and hoisting and resetting the anchor block, to dig like an ordinary dragline machine in an arc of a circle.

The strains of pulling the bucket into blasted rock to fill the bucket are borne entirely by the bucket, the two drag ropes and the two dragline drums. None of the digging strain is transmitted to the hull which remains still and quiet while excavating.

The operator would be stationed on the carriage from which the bucket is suspended. He would be at a point where the bucket would emerge from the water and would look down into the barge as the load was dumped. He would know the exact position of the bucket when digging and hoisting. Depth finders on the carriage would reveal the height of the bank ahead of the bucket at all times.

The herein-described dragline dredge is particularly intended for operation in deep water for the excavation of blasted rock and has many distinct advantages over certain existing types of dredges. As compared with a dredge of the bucket ladder type of comparable actual capacity, its advantages are as follows:

- A. Smaller, lighter and less expensive hull.
- B. Lighter and cheaper machinery.
- C. More easily kept in working condition.
- D. Requires vastly cheaper drilling and blasting.
- E. Will work equally well in depths from 25 to 150 feet with no structural change.
- F. Rock lifted a less distance out of the water.
- G. Can handle large and long pieces of rock in normal operation.
- H. Requires less power.
- I. The strains of pulling the bucket into the blasted rock to fill the bucket are borne entirely by the bucket, the two drag ropes and the two drag drums. None of the digging strain is transmitted to the hull which remains still and quiet while excavating.
- J. Requires no spuds or other bracing connections between the hull and ground.

It will be understood that numerous details of the construction shown and described may be altered or omitted without departing from the spirit of the invention as defined by the following claims.

I claim:

1. A dredge comprising a hull, a dragline bucket, means for raising and lowering said bucket from said hull adjacent one end thereof, an anchor block, means for raising and lowering said anchor block from said hull at approximately its center of buoyancy, a dragline extending between said anchor block and said bucket, and means for hauling said dragline to pull said bucket toward said anchor block when said anchor block is resting on the river bottom beneath said hull.

2. A dredge comprising a hull, a dragline bucket, means for raising and lowering said bucket from said hull adjacent one end thereof, an anchor block, means for raising and lowering said

anchor block from said hull, a dragline extending between said anchor block and said bucket, and means on said anchor block for hauling said dragline to operate said bucket when said anchor block is resting on the river bottom beneath said hull.

3. A dredge comprising a hull, a dragline bucket, means for raising and lowering said bucket from said hull adjacent one end thereof, an anchor block, means for raising and lowering said anchor block from said hull at approximately its center of buoyancy, a dragline extending horizontally from said bucket to said anchor block and vertically from said anchor block to said hull, and winch means on said hull for hauling said dragline.

4. A dredge comprising a hull, an anchor block, means for raising and lowering said anchor block from said hull, a carriage mounted to travel along said hull toward and away from one end thereof, a dragline bucket, means for raising and lowering said bucket from said carriage, a dragline extending from said bucket in hauling relation to said anchor block, and winch means for hauling said dragline.

5. A dredge comprising a hull, an anchor block, means for raising and lowering said anchor block from said hull at approximately the center of buoyancy of said hull, a carriage mounted to travel along said hull toward and away from one end thereof, a dragline bucket, means for raising and lowering said bucket from said carriage, a dragline extending from said bucket in hauling relation to said anchor block, winch means for hauling said dragline, a second carriage counterweighted to compensate for the first said carriage and its load and mounted to travel toward and away from the opposite end of said hull, and means to cause said carriages to travel in predetermined relation to each other toward and away from the center of buoyancy of said hull.

6. A dredge comprising a hull, an anchor block, means for hoisting said anchor block at approximately the center of buoyancy of said hull, a well extending through said hull at its center of buoyancy proportioned to receive said anchor block, a carriage mounted to travel along said hull toward and away from one end thereof, a dragline bucket, means for raising and lowering said bucket from said carriage, a dragline extending from said bucket in hauling relation to said anchor block, and winch means for hauling said dragline.

7. A dredge comprising a hull, an anchor block, means for hoisting said anchor block at approximately the center of buoyancy of said hull, a well extending through said hull at its center of buoyancy proportioned to receive said anchor block, a carriage mounted to travel along said hull toward and away from one end thereof, a dragline bucket, means on said carriage for hoisting said bucket, a well extending through said hull and extending along said hull from one end thereof inward to define the travel of said bucket and being dimensioned to receive said bucket, a dragline extending from said bucket in hauling relation to said anchor block, and winch means for hauling said dragline.

8. A dredge comprising a hull, an anchor block, means for raising and lowering said anchor block from said hull at approximately the center of buoyancy of said hull, a carriage mounted to travel along said hull toward and away from one end thereof, a dragline bucket, means for raising and lowering said bucket from said carriage, a

dragline extending from said bucket in hauling relation to said anchor block, and winch means for hauling said dragline, said winch means comprising a drum journaled on said anchor block, a housing on said anchor block for winch mechanism, and means for excluding water from said housing.

9. A dredge comprising a hull, an anchor block, means for raising and lowering said anchor block from said hull at approximately the center of buoyancy of said hull, a carriage mounted to travel along said hull toward and away from one end thereof, a dragline bucket, means for raising and lowering said bucket from said carriage, a dragline extending from said bucket in hauling relation to said anchor block, winch means for hauling said dragline, said winch means comprising a drum journaled on said anchor block, a housing on said anchor block for winch mechanism, and means for excluding water from said housing, said last-named means comprising a flexible air pressure conduit extending between said housing and said hull and having counterbalanced take-up means to compensate for raising and lowering of said anchor block.

10. A dredge comprising a hull, an anchor block, a dragline bucket, hauling means acting between said anchor block and bucket for operating the bucket, a well extending through said hull at its center of buoyancy proportioned to receive said anchor block, a second well extending through said hull and extending from one end thereof and inward to register with the cutting travel of said bucket and of sufficient width to receive said bucket, a truss extending lengthwise of said hull above said wells, hoisting means car-

ried by said truss for lifting said anchor, a carriage mounted to travel on said truss along said second well, and hoisting means on said carriage for lifting said bucket.

5 11. A dredge comprising a hull, a drag bucket, cable means for raising and lowering said bucket from said hull and arranged for hoisting and dumping the bucket, an anchor block, a drag line extending between said bucket and said anchor 10 block, winch means for hauling said drag line, cable means for hoisting said anchor block toward said hull, and hawser means extending between said hull and anchor block for adjusting said hull longitudinally and laterally relative to said anchor block.

15 12. A dredge comprising a hull, a dragline bucket, means for raising and lowering said bucket from said hull, an anchor block, means for hoisting said anchor block toward said hull, dragline means extending between said bucket and said anchor block, and winch means on said anchor block coacting with said dragline means so as to haul said bucket toward said anchor block, when said anchor block is resting on the river 20 bottom beneath said hull, without transmitting strains to the hull.
